SWITCH DEVICE

Rankin J. Bush, Jeannette, Pa., assignor to The Westinghouse Air Brake Company, Wilmerding, Pa., a corporation of Pennsylvania

Application August 27, 1932, Serial No. 630,733

10 Claims. (Cl. 200—76)

This invention relates to switch devices and particularly to switches of the snap action type for controlling control circuits and particularly the control circuits of electrically driven vehicles, 5 wherein the switch device is actuated and controlled by the control mechanism of the pneumatic brake valve associated with the brake system of the vehicle.

An object of the invention is to provide a 10 switch device, wherein the switch contacts are moved into conductive engagement with a wiping action by reason of a combined longitudinal and angular movement imparted to the movable contact at the time of the engagement with its 15 cooperating contact, thereby insuring clean contact surfaces having low contact resistance.

Another object of the invention is to provide a switch device wherein a switch normally biased toward open position, is closed by a manually 20 actuated operating device associated with the brake valve and retained in closed position independently of the operating device, and wherein the switch is released to open position by a trip mechanism that is manually retained inoperative 25 to release the switch by the operating device.

A further object of the invention is to provide a switch device having the above noted characteristics, wherein adjustable means are provided for determining the operative relation of the operating member with respect to the switch device. 30

A further object of the invention is to provide an improved switch device that is simple and rugged in construction, inexpensive to manufacture, and readily accessible for inspection and repair.

These and other objects of the invention that will be made apparent throughout the further description thereof, are attained by means of 40 the switch device hereinafter described and illustrated in the accompanying drawing, wherein

Fig. 1 is an elevational view of the improved switch device, partially in section, showing the movable switch member in open position; 45 Fig. 2 is a view similar to that of Fig. 1 showing the movable switch member in an intermediate closed position;

Fig. 3 is a top plan view, partially in section, of the switch device with the parts shown in the 50 positions shown in Fig. 2; and

Fig. 4 is a plan elevational view, partially in section of the movable switch contact member.

Referring to the drawing, the switch device 55 comprises a base member 5 preferably made of insulating material, a sheet metal frame 6 for

supporting the switch operating mechanism and which is secured to the base by means of bolts 7, contact supporting brackets 8 secured to the base 5, and a guide support 9 for supporting a tubular guide member 11, the purpose of which 60 will hereinafter appear.

Fixed contacts 12 are mounted upon the brackets 8 and are conductively connected to terminals 13 of the conductors 14 of the electrical control circuit to which the switch device is electrically 65 connected. The fixed contacts 12 are adapted to be conductively connected or bridged by a movable switch member 15, which comprises a metal bridging contact member or arm 16 that is embedded in a block 17 of insulating material 70 and which is provided with contact buttons 18 that are adapted to make butt contact with the fixed contacts 12.

As indicated in Fig. 4, the insulating block 17 is provided with a square metal bushing 19 having 75 a square opening 21 extending therethrough for receiving a square shaft or rod 22, which fits loosely within the bushing 19 so that the block 17 and bridging contact member 16 may move longitudinally with respect to the shaft 22 80 and may have limited universal angular movement with respect thereto, in order that the contact faces of the contact buttons 18 may squarely engage the fixed contacts 12, regardless of slight irregularities in the alignment of the contact 85 faces of the contacts 12.

Movement of the movable switch contact member 15 in one direction along the shaft 22 is limited by a collar 23 that is fixed to the shaft 22 by means of a cotter pin 24. The movable contact member 15 is yieldingly held against the collar 23 by means of a spring 26 which surrounds the shaft 22 and which is disposed between the insulating block 17 and a collar 27 secured to the shaft 22 adjacent one end thereof. 95

The shaft 22 is provided with a cylindrical portion 28 of reduced diameter, which is provided with an enlarged head 29 having a spherical surface 30, the head 29 being adapted to fit within the guide tube 11, as indicated in Figs. 1 and 2, 100 100 and to support the left end of the shaft 22 for longitudinal and angular movement of the shaft, the angular movement being possible by reason of the spherical surface of the head 29 and the reduced diameter of the portion 28.

The right end of the shaft 22 is pivotally supported by means of rocking links 31 that are pivotally connected to a pin 32 carried on the right end of the shaft 22 and to the supporting frame 6 by means of a pin 33. As the links 31 swing 110

from their extreme right position shown in Fig. 1, to the extreme left position shown in Fig. 2, the right end of the shaft 22 is moved through an arc and consequently, angular movement is imparted 5 to the shaft as well as longitudinal movement.

When the shaft 22 is moved toward the left, the contact buttons 18 engage the fixed contacts 12 and arrest longitudinal movement of the switch contact arm 16 before the movement of 10 the shaft 22 is completed and while the shaft 22 is in an angular position with respect to its normal horizontal position. Accordingly, further longitudinal movement of the shaft 22 relative to the switch arm 16, causes the spring 26 to be compressed, so that the contact buttons 18 are maintained in engagement with the contacts 12, by 15 the pressure of the spring 26, as the buttons are moved laterally across the faces of the contacts 12 with a wiping action, in a manner to be herein- 20 after more fully described. Since the switch member 15 is mounted for universal movement upon the shaft 22, the buttons 18 are free to accommodate their position with respect to the contacts 12, so as to secure an extensive surface to 25 surface contact, regardless of slight discrepancies of alignment of the contacts 12.

The switch shaft 22 is actuated by means of a toggle device comprising links 34 and 35 that are pivotally connected by means of a knee pivot 36. 30 The link 34 comprises two flat links disposed on opposite sides of the link 35 and which straddle the collar 27 on the end of the shaft 22. The left end of the links 34 are pivotally connected to the pivot shaft 32, to which the link 31 is pivotally connected. The right end of the link 35 is pivotally connected to a pivot shaft 37 that is fastened to the frame 6 by means of cotter pin 38.

As shown in Fig. 1, the toggle links 34 and 35 are in the released or collapsed position, to which 40 position they have been moved by a spring 39 that is centered by the end of the bushing 11 projecting from the supporting bracket 9, and which is disposed between the guide support 9 and the collar 23 of the shaft 22.

45 The toggle links are moved to the made position, shown in Fig. 2, by means of a bell-crank lever 41 that is pivotally mounted for rotation about a shaft 42 that is fastened to the frame 6 by means of cotter pins 40. The short arm of the 50 lever 41 is bifurcated and constitutes a pair of arms 43 that are disposed on opposite sides of the link 35. A trip shaft 44 connects the free ends of the arms 43 and extends through a relatively large opening 45 in the link 35, so that it may engage 55 the link 35 at points within the opening and move it so as to move the links of the toggle to made position, as shown in Fig. 2, or to cause release movement thereof.

When the toggle links 34 and 35 are in the released position, as shown in Fig. 1, the switch member is in open position. In order to close the switch, the toggle links are moved to the made position shown in Fig. 2 in a manner to be hereinafter described. The first movement of the 65 link 34 causes both longitudinal and angular movement of the shaft 22 as the pivot pin 32 is moved downward in an arc as the link 31 turns about the pivot 33 to a vertical position. Further movement causes an upward movement of the 70 pivot pin 32 as the contact 18 of the switch member engages the contact member 12. As the knee pivot 36 of the toggle passes over center, as when it crosses the center line A, the spring 39 acting on the shaft 22 forces the link 34 of the 75 toggle to turn about the pivot 36 which is then

resting against the stop 46, thus causing a quick vertical or transverse movement of the contacts 18 over the contact members 12, until the angular movement of the shaft is arrested by engagement of the reduced portion of the shaft 22 with the 80 right end of the bushing 11.

The bell-crank lever 41 is adapted to be operated in a counter-clockwise direction for moving the toggle links to the made position, wherein the movable switch member is in the closed position, by means of a rod 47 that is connected to the foot pedal, not shown, of a brake valve device, not shown, for controlling the brakes of a vehicle, not shown. The rod 47 is adapted to be held in elevated position for insuring closed position of the switch, by the foot of the operator, and is moved into inoperative relation with the switch device to permit opening movement thereof, when the rod is moved downwardly as when the foot pedal is moved to emergency brake position by 90 the operator, or by gravity, or a spring, not shown, as when the operator removes his foot entirely from the foot pedal. The upper end of the operating rod 47 is adapted to engage an adjustment screw 48 that is threaded into an arm 49 integral 95 with the bell-crank lever 41, and which is locked in adjusted position by means of a lock nut 51.

As indicated in Fig. 2, the rod 47 has just rotated the bell-crank lever 41 in a counter-clockwise direction and caused the trip shaft 44 105 to move the toggle links from the release position shown in Fig. 1, past their dead center position, so that they may snap to the made position shown in Fig. 2, wherein the movable switch member 15 is in the closed position. The bell-crank lever 41 is biased toward the switch open position, shown in Fig. 1, by means of a spring 52 that surrounds a guide rod 53 that is pivotally connected to the bell-crank lever 41 by means of a pivot pin 54. The guide rod 53 is guided 115 within an opening 55 in a bracket 56 formed integrally with the frame 6 and the spring 52 is disposed between the bracket 56 and the enlarged head 57 of the guide rod 53. When the operating rod 47 is depressed, the bell-crank lever 41 is 120 moved in a clockwise direction by the spring 52 and causes the trip shaft 44 to engage the link 35 and move the knee pivot shaft 36 of the toggle device to a point above the center line A. After the knee pivot shaft 36 passes above the center 125 line A, the spring 39 acting on the collar 23 causes the toggle links to collapse and move with a snap action to the released position, shown in Fig. 1, thereby snapping the movable switch member 15 to the open position shown in 130 Fig. 1, so that any arc drawn between the contacts 12 and the contact buttons 18 is instantly extinguished and the circuit through the switch interrupted.

By employing a toggle device for operating the 135 switch shaft 22 having an over center position, when the toggle is moved to made position, the force exerted by the spring 39, tending to move the switch member 15 to open position, cannot be applied to the operating rod 47 and the force 140 tending to move the operating rod 47 downwardly is, therefore, only that which may be applied by the spring 52, which force is relatively small compared with that exerted by the spring 39.

By reason of the provision of the adjustment 145 screw 48, the operative relation of the switch device to the operating rod 47 and the brake valve device associated therewith, may be varied to suit requirements.

While I have disclosed a switch device that is 150

particularly adapted for controlling the control circuit of a circuit breaker for controlling the motor circuit of a vehicle, and which is associated with a brake valve device for controlling the 5 brakes of the vehicle, it is obvious that the switch device is applicable to other uses and that changes, omissions and additions may be made in the switch device construction without departing from the spirit of the invention.

10 Having now described my invention, what I claim as new and desire to secure by Letters Patent, is:

15 1. A switch device comprising a contact member, an operating shaft slidably supported at one end for longitudinal and angular movement, a pivoted lever for supporting the other end of the shaft for imparting longitudinal and angular movement to said shaft, a movable switch member 20 yieldingly mounted upon the shaft for limited universal movement with respect thereto and adapted to engage said contact member before the shaft has completed its longitudinal and angular movement for causing the switch member to engage the contact member with a wiping 25 movement and an over-center toggle device movable from released position to an over-center made position, so connected to said shaft that it moves to over-center position after the switch member has engaged said contact member, and 30 moves the shaft angularly after it has moved over center.

2. A switch device comprising a support, a contact member mounted thereon, an operating bar supported at one end upon the support for longitudinal and angular movement, a pivoted 35 lever pivotally mounted on the support for supporting the other end of the bar for imparting longitudinal and angular movement to said bar, a movable switch member for engaging said contact member and mounted upon the bar for limited longitudinal movement with respect thereto, a spring disposed between the bar and said switch member for biasing the latter in the direction of said contact member, a spring disposed between said support and said bar for biasing the bar in a direction away from said contact member, and means including an over-center toggle device movable from released to made position for moving the bar longitudinally 45 against the tension of said spring and for imparting angular movement to said bar after the toggle device has moved over center.

3. A switch device comprising a contact member, a movable switch member for engaging said contact member, an operating shaft for supporting said switch member and slidably supported at one end for longitudinal and angular movement, a pivoted lever for supporting the other end of said shaft for moving said shaft angularly and longitudinally for moving said switch member into engagement with said contact member and a toggle device for moving said lever movable to made and released positions and so connected to said shaft that it retains the said 55 shaft and switch member in closed position when the toggle device is in made position.

4. A switch device comprising a contact member, a movable switch member for engaging said contact member, an operating shaft for supporting said switch member and slidably supported at one end for permitting longitudinal and angular movement of said shaft, a toggle device, means including a link of said toggle device pivotally connected to the other end of said shaft, 70 for moving the shaft longitudinally for moving

said switch member into engagement with said contact member and for imparting angular movement to said shaft for moving said switch member transversely over said contact member during the final movement of said shaft.

5. A switch device comprising a contact member, a movable switch member for engaging said contact member, an operating shaft for supporting said switch member and slidably supported at one end for permitting longitudinal and angular movement of said shaft, a toggle device, means including a link of said toggle device pivotally connected to the other end of said shaft, for supporting said other end of said shaft for imparting angular movement thereto as the shaft is moved longitudinally by said toggle link for moving said switch member into engagement with said contact member, and means having a lost motion connection to said toggle device for moving it to its operative positions.

6. A switch device comprising a contact member, a movable switch member for engaging said contact member, a spring associated with said switch member for moving said switch member 100 to open position, a toggle device having made and released positions, and so connected to said switch member that when the toggle device is in made position it holds the switch member in closed position against the action of said spring, 105 and a second spring acting on said switch member and adapted to be placed under tension when said toggle is moved from released to made positions, and adapted to cause release movement of said toggle.

7. A switch device comprising a contact member, a movable switch member for engaging said contact member, a spring associated with said switch member for moving said switch member to open position, a toggle device having made 110 and released positions and so connected to said switch member that when the toggle device is in made position it holds the switch member in closed position against the action of said spring, means for moving said toggle device toward made 115 and released positions, and a second spring adapted to be tensioned by said means for actuating said means for initiating movement of said toggle to released position.

8. A switch device comprising a contact member, a movable switch member for engaging said contact member, a spring associated with said switch member for moving said switch member to open position, a toggle device having made and released positions and so connected to said 120 switch member that when the toggle device is in made position it holds the switch member in closed position against the action of said spring, means for moving said toggle device toward made and released positions, a second spring adapted 125 to be tensioned by said means for actuating said means for initiating movement of said toggle to released position, and a manually operated means for actuating said means for moving said toggle to made position.

9. A switch device comprising a contact member, a movable switch member for engaging said contact member, a spring associated with said switch member for moving said switch member to open position, a toggle device having made 130 and released positions and so connected to said switch member that when the toggle device is in made position it holds the switch member in closed position against the action of said spring, means for moving said toggle device toward made 135 and released positions, and a second spring adapted to be tensioned by said means for actuating said means for initiating movement of said toggle to released position, and a manually operated means for actuating said means for moving said toggle to made position.

and released positions, a second spring adapted to be tensioned by said means for actuating said means for initiating movement of said toggle to released position, a means movable manually a predetermined distance and movable relative to and actuating said means for moving said toggle to made position, and adjustable means cooperating with the first and second said means for determining the degree of relative movement of the second said means with respect to the first said means.

10. In a switch device, the combination with a contact member, a support therefor, a switch member movable into contact with said contact member, an operating shaft for said switch member movable longitudinally for moving the switch member into contact with said contact member and movable angularly for moving said switch member transversely of said contact member, a

spring normally biasing said shaft in a direction away from said contact member, and means for supporting one end of said shaft for longitudinal and angular movement, means for limiting angular movement of said shaft, and an operating means for imparting longitudinal and angular movement to said shaft comprising a pair of toggle links connected by a knee pivot, and connected respectively to the other end of said shaft and to said support by separate pivots, the said knee pivot being movable from release position of said links to made position thereof against the action of said spring and across a center line through said pivots so that said other end of said shaft is moved angularly by said spring acting with said toggle link after said knee pivot has crossed said center line.
